CUTTING MACHINE KNIFE SHARPENER AND
STANDARD PROTECTOR

David Bernard Ashman, Baltimore, Md.

Application June 4, 1937, Serial No. 146,393

4 Claims. (Cl. 51—250)

This invention refers to sharpening devices for cloth cutting machines having straight knife blades. It has among its objects to provide a sharpener of this type that may be placed against the support standard and the knife blade without removing same from their positions on the table; that will not interfere with the movement of the knife blade or obstruct the view of the operator in regard to the operative parts of the machine and sharpener; that will be adjustable in many variable and desirable ways; will be substantial and protective in regard to the user and the machine, and will be so provided that extra sharpening stones may be placed convenient to the user, and the device. Other objects will become apparent as the invention is more fully set forth.

It has been customary to sharpen the straight blades of many cloth cutting machines by removing same or utilizing a hone held in the hand of the operator. This method of sharpening frequently causes improper sharpening and damage to the structure of the machine. The damage is caused by the rubbing of the hone or stone against the surface of the cutting machine structure. In this device the stones of the same, used for sharpening, are definitely and positively located out of the way and come only in contact with the knife blade, in a manner that is predetermined to suit the cutting edge to be provided. It is brought against the cutting machine in its normal position and slides around the standard with its base slotted in such a manner as to keep it out of the line of travel of the blade and thereby not obstruct the latter or cause its breakage.

In the construction indicated in the drawings:—

Figure 1 represents a plan view of a sharpening device embodying this invention mounted about a straight-knife cutting machine,

Figure 2 is a front elevation of Figure 1,

Figure 3 is a side elevation of Figure 1, partly in section.

Similar reference characters refer to similar parts throughout the drawings.

In the drawings, 1 represents a conventional type of cutting table, on which a straight-knife cloth cutter throw plate 2 is mounted with its cutting blade 3. The cutter blade or knife reciprocates in the guide slot 4 and a support standard 5, being operated in the conventional manner by the motor and connections 10. The support standard has a suitable rounded back 6 that is enlarged to strengthen and stiffen it. A base plate 5 is provided for the sharpening device having a

U-shaped slot 8 arranged to fit closely around the back 6, and with its mouth portion 9 fanned outwardly to avoid interfering with the movement of the knife blade 3 of the cutting machine. The base plate is preferably formed as indicated in the drawings, with its peripheral portion 11, quasi-circular in form and provided with an upwardly projecting ridge 12. A hollow triangular back frame 13 is mounted on the upper surface plane of the base plate 7, and has its apex portion 10 arranged at 15, to take the rear surface 16 of a back holding member 17. This member is provided with a front groove 18 that fits the back portion of the support standard as indicated in the drawings. Screws 19, suitably placed secure the member to the apex portion. The member 17 is made high enough to reach the under surface of the element 22 that supports the motor for operating the cutter. This distance will vary to suit a cutter machine intended for "shear work", "general work"; "high layers"; "flannellettes"; and "burlap bags", as the case may be. A suitable number of supporting columns 23 are provided on the base plate, positioned as indicated on the drawings, serving as journal members for arms 24, which adjustably hold the manipulators. The manipulators consist of plungers 26 that can be adjustably reciprocated in the arms 24 to suit the knife to be sharpened.

A three-member body is attached to the plunger 26, in each case, and consists of a sharpening stone holder 27, a positioning rod 28, and a handle 29. The holder 27 is formed at 30 to receive a sharpening stone, which is clamped securely in place by a flat plate 31, through the use of screws 32. The rod 28 is integral with the plunger 26 and rests on the surface of the base plate and may be given a tilting movement thereon by reason of the rounded portion 25. The handle 29, screw 37 is connected with the plunger 26 by a central shaft 33, passing through a hole 34 in the latter, and turns the holder 27 in unison with its movement, through the same shaft 33, which connects and holds both in same relative positions on the plunger 26. The plunger member 26 has prongs 35 projecting from it, that limit the turning movements of the handle 29 and holder 27, and in addition is split in the middle at 36 to permit adjustment in a horizontal plane, as indicated. Screws 37 and slots 38 are provided for this adjustment. A spring 39 is mounted on, and attached at 20, to the base plate and connected with its respective arm 24, serving normally to keep the parts connected with the latter away from the knife of the cutter machine and against

the ridge 12. The operation of the device will explain the functions of the parts adequately.

In the use of the device, the sharpening stones are clamped in the supports at 30 by the flat plates 31 and positioned against the sides of the knife to be sharpened by adjusting the plunger members 26, at their middle sections 36 to suit the angular cut to be made on the knife edges. This provides a permanent angle for grinding 10 the knife.

The plunger is then extended or inserted suitably in the arm 24 and clamped in this position by the screws 21 provided for the purpose. The knife is set into operation and reciprocates vertically at high speed. The operator holds the handles 29 and twists the stone holders 27 to suit the work. The stones are kept in the same angular plane with respect to the knife and therefore grind off a uniform edge; but being 15 twisted or rotated within the limits arranged for, sharpen the knife uniformly. The handles are under the stress of the springs at all times, tending to bring them away from the knife being ground, when the operator releases the manual 20 pressure forcing them close to the knife. This gives a more sensitive grinding action and prevents the stones from scoring and being in the way of the knife, unless positively kept there by the operator. The stone holder is so arranged 25 that the stones may be quickly replaced or turned in it, enabling it to make maximum use of their surfaces and material.

The triangular form of the back frame 13 enables the device to be placed with the hand, 30 easily on or off the cutter, and its hollow central portion to hold stones or tools to be used with it. The holes 40 are provided for the convenience of the operator, to lift the device. The sides of the triangular back frame 13 permit the operator to 35 lay additional stones flat against same and hold them by hand at the most usable angle desired against the knife, and also utilize the holes 40 for the insertion of his fingers in getting a strong grip on the stones. The bottom of the knife, also 40 known as its lower portion, may be specifically sharpened by tilting the stone holders suitably, so that the stones come into contact with same 45 at an angle vertically acute to that of the knife surface.

50 While but one form of the invention is shown in the drawings, it is not desired to limit this application for patent to the particular form indicated, except as limited by the prior art, as it is appreciated that other forms of construction 55 might be used, employing the same principles and coming within the scope of the appended claims.

Having thus described the invention, what is claimed is:—

60 1. A device of the class described comprising in combination, a base plate adapted to rest on a cutter machine table, and having its front portion arranged with a fan-like opening to permit the base to be fitted against the support standard of the cutter machine and out of the travel of the knife thereof, a column member mounted on the base plate, an arm pivoted on the said member, a plunger adjustably secured in the arm, a 65 holder attached to the plunger and adapted to

be positioned adjustably in variable planes with respect thereto, a supporting stem for the holder arranged to support same in variable angles longitudinally and transversely with respect to the cutting edges of said knife, a handle in the holder having an enlarged winged body, a stone support in the holder connected with the stem and the handle, the handle being arranged for manual manipulation of the stone support. 5

2. A device of the class described comprising 10 in combination, a base plate adapted to rest on a cutter machine table, and having its front portion arranged with a fan-like opening to permit the base to be fitted against the support standard of the cutter machine and out of the travel of 15 the knife thereof, a column member mounted on the base plate, an arm pivoted on the said member, a plunger adjustably secured in the arm, a holder attached to the plunger and adapted to be positioned adjustably in variable planes with 20 respect thereto a supporting stem for the holder arranged to support same in variable angles, a handle in the holder having an enlarged winged body, a stone support in the holder connected with the stem and the handle, the handle being 25 arranged for manual manipulation of the stone support to position the stone against longitudinal and transverse cutting edges of the said knife, means for securing the base plate to the said support standard, and ridge means for controlling the movement of the holder. 30

3. A device of the class described comprising in combination, a base-plate formed for attaching itself to a cutter machine and out of the line of travel of its knife, columns mounted on the 35 base-plate, arms journaled on the columns, plungers adjustably attached to the arms and provided with movable sections to permit them to be adjustably arranged thereon, a plurality of stone holders attached to the plungers and 40 adapted to be variably positioned thereon, means for controlling the movement of the plungers to and from the knife and location and position of the stone holders in relation thereto, and resilient means for normally positioning the holders and arms in predetermined locations, and means for retaining the base plate to the cutter machine in rigid relation thereto sharpening 45 means in the stone holders, adapted to be positioned by the said parts hereinbefore mentioned 50 to provide a longitudinal cutting edge and a transverse cutting edge on said knife.

4. A sharpening device for the knife means of a cloth cutting device, comprising in combination, a base adapted to rest on said device, an arm mounted on said base, an arm rotatable to and from the longitudinal plane of said knife means, a plunger in said arm adapted to permit reciprocating and rotating movements therein, prongs on the said arm, a holder attached to the plunger and limited in its movement by said prongs, adjustment means in the plunger to permit the adjustment of the holder angularly with respect to the axis of the plunger, sharpening means in the holder adapted to sharpen the knife means 60 on its cutting edges arranged in divers planes by the rotation of the plunger aforesaid and said adjustment means, and the said arm. 65
